UNITED STATES PATENT OFFICE.

ALOYSIUS McHUGH, OF DUBOIS, PENNSYLVANIA.

SPLICING-BAR.

SPECIFICATION forming part of Letters Patent No. 379,176, dated March 6, 1888.

Application filed June 17, 1887. Serial No. 241,658. (No model.)

To all whom it may concern:

Be it known that I, ALOYSIUS McHUGH, a citizen of the United States, residing at Dubois, in the county of Clearfield and State of Pennsylvania, have invented a new and useful Improvement in Splice-Bars, of which the following is a specification.

My invention relates to improvements in splice-bars for the joints between railroad-rails; and it consists in a certain novel construction and arrangement of parts for service, fully set forth hereinafter, and specifically pointed out in the appended claim.

In the drawings, Figure 1 is a view of the outside of a rail-joint provided with my improved bar. Fig. 2 is a similar view of the inside. Fig. 3 is a section on the line *y-y*, Fig. 1. Fig. 4 is a transverse section of the coupling on the line *x-x* of Fig. 1. Fig. 5 is a detail perspective view of the parts of the invention detached.

Referring to the drawings by letter, A designates the ends of two rails which are spliced together by my improved device, and B is the chair under the ends of the same, comprising the base-plate B', having a flange, *b*, on one side provided with a beveled outer side, and a flange, C, on the inner side adapted to fit over the lower inner flange of the rail. The edge of the said flange, close to the body of the rail, is turned up to form a lip, D, inclined inwardly slightly, and adapted to bear at the upper edge against the under side of the upper flange, *a*, of the rail.

E designates a flat bar adapted to bear at the lower edge against the beveled side of the flange *b* and at the upper edge against the under side of the upper flange, *a*, of the rail in the same manner as the lip C on the opposite side of the rail. It will be noticed that the bar E is also inclined inwardly, and therefore bears squarely on the beveled surface of the flange *b*. A slight rib, *e*, is formed on the inner side of the bar E, which is adapted, when the same is in position, to bear down upon the upper side of the lower flange, *a'*, of the rail, to hold the same down on that side.

F F are openings formed through the flange C, and notches are formed in the edges of the rails to align with the said openings, and

spikes G are passed through the said openings and notches and driven into the ties of the railroad.

It will be seen that the heads of the spikes bear down upon the upper side of the flange C, and therefore when the bar E is not in place there is nothing to prevent the rails from being removed from the splice bar without displacing or disturbing the chair. The said rails may also be placed in the chair again and locked in position as before without altering the position thereof.

The lower edge of the bar E is notched, as seen at H, and openings I are formed in the base-plate B' to align therewith; also, small notches are formed in the lower flange, *a'*, of the rail to align with the said openings I and notches H, and spikes G', similar to the spikes G, are passed through the said aligned openings and notches and driven into the ties. 70

When the rails break, or it is desired to remove them for any reason, the spikes G' are drawn and the bar E removed, when the ends of the rails which are in the coupling or splice-bar will be free. A small notch, *h*, is formed in the lower edge of the bar E, to enable the said bar to be readily removed by inserting a bar or pry in the said notch. 75

When a weight is on the rail, the pressure is exerted on the upper edges of the lip D and the bar E, and as these are inclined the pressure is distributed, and, owing to the disposition of the parts of the device, there can be no displacement thereof. It will be seen that the bar E cannot slip out of place, as the lower edge thereof presses down firmly on the beveled side of the flange. The rib *e* on the inner side of the bar E bears upon the lower flange of the rail and thus holds it in place. 80

Small perforations *h' h'* are formed in the plate B' about the center to allow sand and water which may enter the chair to escape. 85

Having thus described my invention, I claim—

The combination, with the rails having notches therein, of the chair B, comprising the plate B', provided with perforations *h'* therein, beveled flange *b*, and the flange C, having the lip D on the edge thereof, bar E, having the notch *h* in the lower edge and resting at the 90

lower edge on the said beveled flange, rib *e* on the inner side of the said bar, and the spikes *G*, to pass through openings in the bar *E* and chair *B*, and also through aligned openings in the rails, substantially as and for the purpose set forth. In testimony that I claim the foregoing as my

own I have hereto affixed my signature in presence of two witnesses.

ALOYSIUS McHUGH.
